HANDBAG CLASP

Richard Koret, New York, N.Y., assignor to Koret, Inc.,
New York, N.Y., a corporation of New York

Filed Dec. 30, 1964, Ser. No. 83,216

Term of patent 3½ years

(Cl. D87—2)

FIG. 1

FIG. 1 is a top plan view of a handbag clasp showing my new design;

FIG. 2 is a side elevational view thereof; and

FIG. 3 is an end elevational view thereof.

The fragmentary broken-line showing of a handbag is for illustrative purposes only.

I claim:

The ornamental design for a handbag clasp, substantially as shown and described.
